(57) **CLAIM**

The ornamental design for a handle for an applicator of an apparatus for personal skin treatment, as shown and described.

DESCRIPTION

This application is related to U.S. Design Application for Patent filed concurrently herewith and bearing the title of a Skin Illumination Module Attachment for an Applicator of an Apparatus for Personal Skin Treatment and identified by Ser. No. 29/387,278.

FIG. 1 is a perspective view of our new design of a handle for an applicator of an apparatus for personal skin treatment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of parts of the drawings is included for the purpose of illustrating use and environment and forms no part of the claimed design.
